UNITED STATES PATENT OFFICE

WILLIAM A. McCURDY, OF DULUTH, MINNESOTA

FERRULE FOR BLASTING CARTRIDGES

Application filed June 15, 1938. Serial No. 285,588.

This invention relates to a new and improved blasting cartridge construction and more particularly to a ferrule adapted to be placed upon a blasting cartridge to maintain the firing cap in place in the cartridge.

In the use of cartridges for blasting they are commonly placed in a drilled hole in the material to be blasted after a cap has been inserted in the cartridge and firing means, such as a fuse, or electric wires have been secured to the cap. The hole is then tamped with loose material to retain the cartridge in place and to properly direct the effect of the blast. In actual practice accidents have occurred due to rock or other loose material falling on the priming cartridge and striking the cap so that the same is exploded. There is also the difficulty that sometimes, in placing and tamping the cartridge, the cap is pulled from the cartridge by the fuse or wires.

It is an object of the present invention to provide a blasting means having means for securing the firing cap in place and protecting the same.

It is also an object to provide a construction of this character in which the cap is held in place by a sleeve fastened upon the cartridge.

It is an additional object to provide a sleeve which is cup-shaped in formation and adapted to be placed over an end of the cartridge.

It is a further object to provide a construction which is simple in design and construction and adapted for commercial production.

Other and further objects will appear as the description proceeds.

I have illustrated a preferred embodiment of my invention in the accompanying drawings, in which

Figure 1 is a side view of one form of construction;

Figure 2 is a similar view of a modified form of construction; and

Figure 3 is a section taken on line 3—3 of Figure 1.

In the drawings, the cartridge has been designated 11 and in Figure 1 is provided with the tubular sleeve 12. A cushion 13, 50 which may be formed of rubber, felt or asphaltum, is placed inside of the sleeve 12. The sleeve 12 is secured in place by pins 14 which are forced into the cartridge 11. These pins may be formed of wood or other material. The firing cap 15 is shown inserted into the cartridge and the firing connections 16 lead from the cap past the end of the sleeve 12. These connections may be electric wires or fuses.

In the form of construction shown in Figure 2 the cartridge 17 has the cup-shaped cap 18 slipped upon its end. The sleeve 18 is also provided with a cushioned lining 19 and is secured in place by the pins 20. The firing cap 21 is located in the end of the cartridge 17 and the firing connections 22 extend through an opening 23, formed in the end of the sleeve. An end of the sleeve is also provided with a cup-shaped seat or socket 24 for receiving a charging stick 25 which may be used to seat the cartridge properly in the blasting hole.

Either form of construction may be used and both adequately protect the cap against 75 accidental discharge by material falling upon the cartridge. They also prevent it from being easily withdrawn from the cartridge. The form of construction shown in Figure 2 has the additional advantage of protecting 80 the end of the cartridge and forming a seat for use in forcing the cartridge into the blast hole. The cushioning layers 13 and 19 are optional and may or may not be used. In some circumstances they may prove desirable. 85

While I have shown certain preferred forms of my invention by way of example, it is capable of further modification to meet varying conditions of use, and I contemplate such changes and modifications as come with- 90

in the spirit and scope of the appended claim.

I claim:

A blasting article comprising, in combination, a cartridge, a hollow member mounted upon the cartridge and adapted to hold in proper position the detonating cap, and a cushion inserted between the hollow member and the blasting cartridge.

Signed at Virginia, Minnesota, this seventh day of June, 1928.

WILLIAM A. McCURDY.
